SUPPORT FOR SKATE RUNNERS AND PROCESS OF MAKING SAME

Filed Jan. 24, 1928

52 Inventor:
Gustav E. Schmidt,
Cheever & Cox Citys.

Patented Apr. 2, 1929.

UNITED STATES PATENT OFFICE.

GUSTAV E. SCHMIDT, OF CHICAGO, ILLINOIS.

SUPPORT FOR SKATE RUNNERS AND PROCESS OF MAKING SAME.

Application filed January 24, 1928. Serial No. 249,046.

My invention relates to ice skates, and more particularly to an ice skate having an improved form of construction of support for the runner or blade of the skate.

5 One of the objects of my present invention is to provide an improved blade or runner support for an ice skate which is light in weight yet provides a mounting in which the runner or blade of the skate is secured 10 of pronounced ruggedness and strength, and which holds the runner in true position without danger of warping or bending.

Another object of my present invention resides in the provision of a tubular support 15 for the blade or runner formed of sheet metal, preferably sheet steel, and bent or folded so as to provide a reentrant seat or pocket having reinforced side walls and which pocket is adapted to snugly receive the runner or blade of the skate.

20 Yet another object of my invention resides in the process by which my improved tubular support may be formed from a strip of sheet metal by means of a bending or 25 folding operation and wherein the metal is provided with a reentrant pocket for the reception of the skate runner and wherein the free edges of the metal blank are interlocked to provide a substantial one-piece construction of great strength and compact arrangement.

This and other objects of my invention will be apparent from a perusal of the following specification, and taken in connection with the accompanying drawings where- 35 in,

Figure 1 is a side view of my improved 40 skate.

Figure 2 is a section of line 2—2 thereof.

Figure 3 is a perspective view of a fragment 45 of the sheet metal blank that we use.

Figure 4 is a perspective view showing the first operation involved in forming the blank.

Figure 5 shows the next or the folding 50 operation.

Figure 6 shows a view of the top portion of the tubular support.

In general, an ice skate embodying my invention comprises the usual toe plate 2 and heel plate 4, the former carrying the usual toe cup 6 and the latter the heel cup 8. In addition there is provided the usual toe brace 10. The two cups and the brace are welded, soldered or riveted to the support carrying the runner. My present invention

60 relates to the construction of the tubular support and the manner of holding the runner mounted therein and also to the process by which the support is formed and the runner assembled in position.

In order clearly to explain the construction of my improved support I will describe it by reference to the process in which it is made. I prefer to start with a sheet metal 65 blank 12, preferably of sheet steel and preferably of rectangular shape and relatively long. If desired a strip of pronounced length may be used and the separate blanks cut from this strip. However, in the present 70 instance I shall refer to a strip of the proper length for forming one tubular support. A fragment of this blank is shown in Figure 3 of the drawings. In the first step in the 75 formation of this blank I bend one of the marginal edges thereof downwardly to provide a flange 14 and I bend the opposite marginal edge, which is considerably wider, 80 downwardly also to provide another flange 16 which has a right angle extension 18 projecting horizontally as shown in Figure 4 and this flange in turn is extended again 85 upwardly to provide a portion of flange 20 lying parallel and spaced apart from the flange 16, as clearly shown in Figure 4. These flanges extend the length of the blank. 90 Either simultaneously with the bending of these flanges, or before or after, I also provide the blank 12 longitudinally thereof with a substantially centrally located up- 95 standing hollow ridge 22 which in cross section is of U shape, being relatively deep with respect to its width. This hollow ridge is provided with two parallel upstanding walls 24 and 26 joined by a top flange 28 which in fact is a continuation of the walls 24 and 26 only extending at right angles thereto. So 100 also, simultaneously with the formation of the flanges 14, 16, 18 and 20 and, or, with the formation of the ridge 22 or before or there- 105 after, I also cut from the end of the blank 12 the two spaced apart tongues 30 and 32. The material of the blank is cut away where the ridge is located to provide the slot 34.

110 My next step is to fold the blank into the form shown in Figure 5. In this operation I prefer to swing or curl the longitudinal edges of the blank on each side of the ridge 22 upwardly so as to form curved side walls 36 and 38 and the free flanged ends of these walls are carried upwardly to a point above the top portion 28 of the ridge and so that

the flanges 16, 18 and 20 overlap the flange 14 and interlock therewith, with the lower portion 40 of the flange 14 lying on the top 28 of the ridge and the lower portion 42 of the flange 16 lying also on the top 28 of the ridge. Thus I provide two tubular portions 44 and 46, one lying on each side of the walls 24 and 26 of the ridge with the flanges 14, 16, 18 and 20 interlocking and overlying 10 and upon the flange 28 of the ridge all serving to form a very compact and strong tubular construction with the recess or pocket formed by the walls 24 and 26 of the ridge and which pocket lies between the tubular 15 portions 44 and 46. Preferably after a tube is bent into form, as shown in Figure 2, I also die-press or pinch the tongues 30 and 32 together in the manner illustrated in Figure 5 to provide a relatively blunt or round- 20 ed nose both at front and back of blank and with an intervening slot 34 lying in the plane of the pocket formed by the walls 24 and 26. Each end of the blank is formed similarly except that the front is given a 25 slight upward turn to correspond with the upturn of the runner.

The skate runner or blade is inserted in this pocket and between the walls 24 and 26 and snugly in contact therewith. The 30 upper edge 48 of the runner formed abuts the end face of the wall 28 of the ridge and by reason of the depth of this pocket the 35 skate blade is firmly held between the two side walls 24 and 26 and the spaced apart tubes 44 and 46 in rigid relation throughout its length. I prefer to solder the runner 50 in position as shown by means of the solder 52. When the runner is seated in the pocket, the front portion of the runner 54 will seat 40 in the front slot 34, while the rear portion of the runner will seat in the rear slot. One of the final finishing steps consists in removing the metal of the ridge from a point 45 removed from the front and rear inwardly as indicated at 52 and 54 in the drawings.

By reference to the foregoing it will be seen that I have provided a very strong and compact arrangement for supporting the 50 skate runner throughout its length in a very firm manner so as to preclude any warping or twisting of the blade out of its socket. I also provide a very convenient and economical construction whereby the support is formed of a single blank of sheet metal 55 by simple folding and bending operations and wherein the walls of the blank are provided with a very rigid pocket or recess and formed on each side thereof with tubular supports merely by appropriately bending the sheet of metal, preferably upwardly and upon itself to form the spaced apart tubes and the intermediate pocket. It will be seen that the pocket is originally formed by the 60 upstanding ridge and that the tubes are formed by curling the free edges of the

blank upwardly and above the ridge so as to rest on the top of the same. In this construction it will be seen that the folded portions lying longitudinally of the free edges of the blank, by reason of their interlocking 70 engagement with each other and upon top of the ridge, provide a most compact and rugged construction for the purposes described.

Having thus described my invention, what 75 I claim as new and desire to secure by Letters Patent is:—

1. An ice skate having a support formed of sheet metal bent to provide a longitudinally extending pocket, the walls forming 80 the pocket being extended outwardly thereof and curved upwardly to a point above the bottom wall of said pocket to overlie the same in interlocking relation and a skate runner seated in said pocket. 85

2. A skate having a longitudinally extending support consisting of a blank of sheet metal having a substantially oval shape with the top and bottom thereof substantially flat, the bottom wall being formed of a re-entrant fold having parallel spaced apart sides and a bottom wall extending parallel to and in contact with the top wall to provide a longitudinally extending pocket, the upper wall of said support including interlocking 95 portions of the free longitudinal edges of the original blank and a skate runner mounted in said pocket. 90

3. A skate having a tubular support formed of a sheet metal blank, said blank 100 being tubular in shape with one wall of the tube extending inwardly to provide a re-entrantly disposed pocket, the free edges of the blank being interlocked and forming a part of the opposite wall and a skate runner 105 mounted in said pocket. 105

4. In an ice skate the combination of a runner support of tubular cross section having its upper wall provided with upstanding interlocking flanges and with its lower 110 wall provided with an inward fold having spaced apart walls and the intercommunicating facial wall contacting with the inner surfaces of the interlocked flanges of the upper wall and a runner mounted in said 115 re-entrant fold.

5. An ice skate having a runner support of tubular cross section, the upper portion of the support having an upstanding portion formed by interlocking flanges, said support 120 having a re-entrantly disposed seat therein on its end surface and a skate runner mounted in said seat, said skate runner being reinforced by tubular portions formed on each side of the seat. 125

6. The herein described process of forming an ice skate runner support which comprises providing a substantially rectangular form of sheet metal with marginal laterally extending flanges and with an inter- 130

mediately and oppositely located hollow flange having spaced apart substantially parallel walls, bending the free marginal flanges to overlie the upper wall of the hollow flange and to interlock therewith so as to provide tubular portions on each side of the hollow flange.

7. The herein described process of forming a tubular support for an ice skate runner which comprises providing a strip of sheet metal with laterally extending marginal flanges one of which is of substantially U shape cross section and providing the strip with a hollow flange having parallel spaced apart walls and a continuous piece adjoining said walls, said hollow flange extending in a direction opposite to the first mentioned flanges and curling said marginal flanges over and above said hollow flange in interlocking engagement with each other and in contacting engagement with the top surface of the hollow flange, to provide tubular reinforcing members on each side of the hollow flange.

25 8. The herein described process of forming a runner support for an ice skate which comprises bending a rectangular strip of sheet metal to provide longitudinally extending marginal flanges, at least one of which flanges is provided with a plurality of bends to form an interlock and providing the strip with a longitudinally extending substantially centrally located outstanding hollow ridge having parallel walls and a substantially transversely and continuous base, said walls and ridge extending in opposite directions to the first mentioned flanges, and providing the ends of the blank with substantially rounded tongues on each

40 side of the ridge with the metal of the blank

cut away between the tongues, curling the flanges and side of the blank over the top wall of the ridge and causing them to interlock and abut said wall and pressing the tongues together to form a rounded nose, 45 and inserting a skate runner in said hollow ridge with the ends of the runner in the slots formed by the spaces between the pressed together tongues.

9. The herein described process of forming a runner support for an ice skate which comprises bending a rectangular strip of sheet metal to provide longitudinally extending marginal flanges, at least one of which flanges is provided with a plurality 50 of bends to form an interlock and providing the strip with a longitudinally extending substantially centrally located outstanding hollow ridge having parallel walls and a substantially transversely and continuous 55 base, said walls and ridge extending in opposite directions to the first mentioned flanges, and providing the ends of the blank with substantially rounded tongues on each 60 side of the ridge with the metal of the blank 65 cut away between the tongues, curling the flanges and side of the blank over the top wall of the ridge and causing them to interlock and abut said wall and pressing the tongues together to form a rounded nose, 70 and inserting a skate runner in said hollow ridge with the ends of the runner in the slots formed by the spaces between the pressed together tongues, and cutting away 75 a portion of the upstanding ridges at the front and rear of the upper surface of the support.

In witness whereof, I have hereunto subscribed my name.

GUSTAV E. SCHMIDT.
